Joseph E. Lodge, Baltimore, Md., assignor to
Western Electric Company, Incorporated, New
York, N. Y., a corporation of New York

Application January 7, 1948, Serial No. 899

8 Claims. (Cl. 146—174)

1

This invention relates to strainers, and more particularly to apparatus for effecting a rapid change of straining elements used in such apparatus.

Extrudable materials, such as rubber compounds, or the like, are used extensively with extruding machines which apply an insulating cover or jacket of such material around an advancing core. Such compounds usually consist of a number of ingredients which are mixed together in a suitable mixing machine, such as a machine commonly referred to as a "Banbury mixer." Frequently, the mixed compound contains certain unmixed lumps of the various ingredients or lumps of foreign matter, which must be removed or strained from the compound before the material is supplied to the extruding machines.

Various types of strainers are employed to strain the compound immediately after it has been discharged from the mixing machine. In general, they consist of a cylinder having a rotating stock screw therein which forces the mixed compound through a screen suitably positioned across the end of the cylinder. When the screen becomes clogged up with foreign matter and lumps of unmixed material, it is necessary to either clean the screen or replace it with another screen. In either case the screen changing operation on the present type of straining apparatus requires a substantial amount of manual labor and results in a substantial loss of operating time for the straining machine. Since the extruding apparatus requires a continuous supply of compound, the shutdown periods of the straining apparatus must be as short as possible.

An object of the invention is to provide new and improved strainers.

Another object of the invention is to provide new and improved apparatus for effecting a rapid change of straining elements in strainers.

An apparatus embodying certain features of the invention comprises a strainer head arranged to be mounted on the end of a cylinder having a stock screw rotatably mounted therein for conveying a compound to be strained into the straining head, a plurality of belt-like strainer screens slidably positioned across the opening of the strainer head, a plurality of perforated plates slidably positioned across the opening of the strainer head contiguous to the screens to support them as the stock screw forces the compound through the screens and means for holding the perforated plates in position as the compound is forced therethrough.

2

A complete understanding of the invention will be had from the following detailed description of a specific embodiment, when read in conjunction with the appended drawings, in which:

Fig. 1 is a plan view of a strainer head and an associated screen changing apparatus embodying specific features of the invention;

Fig. 2 is an end view of the strainer head shown in Fig. 1;

Fig. 3 is a vertical, sectional view taken along line 3—3 of Fig. 2;

Fig. 4 is a vertical, sectional view taken along line 4—4 of Fig. 2;

Fig. 5 is an enlarged, fragmentary, sectional view of a portion of the apparatus taken along line 5—5 of Fig. 2, and

Fig. 6 is an enlarged, fragmentary, sectional view taken along line 6—6 of Fig. 2.

Referring now to the drawings, and more particularly to Fig. 1, there is illustrated a strainer head assembly indicated generally by the numeral 10, which head comprises a cylindrical body portion 11 having an annular flange 12 provided on one end thereof and a rectangular flange 13 provided on the other end thereof. The flange 12 of the head 10 is arranged to be bolted to the end of a tuber cylinder, a portion of which is indicated by the numeral 14, which cylinder is provided with a stock screw 15 arranged to be rotated in a bore 16 provided in the cylinder. The head 10 is provided with a bore 17 equal in diameter to the bore 16 to receive the end of the stock screw 15 which extends a substantial distance into the head 10.

The bore 17 (Fig. 6) flares outwardly at the opposite end of the head 10 to communicate with a rectangular opening 18 embraced by the flange 13. A shoulder 19 is provided on each horizontal side of the flange 13 which is flush with the face of the vertical legs of the flange. A hardened steel strip 20 is pressed into grooves provided in the shoulders 19—19 and the vertical legs of the flange 13 so that one end thereof projects slightly beyond the surface of the shoulders and the vertical legs of the flange.

An elongated plate 21 is secured along the upper horizontal portion of the flange and an elongated plate 22 is secured along lower horizontal portion of the flange 13, which plates coact with

their respective adjacent shoulder 19 to form horizontal grooves 23—23 in the opening 18 of the flange 13.

A channel-shaped support 24 is formed integrally with the head 10 on the right side of the flange 13 (Fig. 2) and is provided with a shoulder 25 in the upper leg thereof and a groove

26 in the lower leg thereof (Fig. 2) which communicate with grooves 23-23 provided in the horizontal sides of the flange 13. A rectangular slot 27 is provided at the end of the support 24 (Fig. 1) to provide an opening through which screens 30, 31 and 32 are advanced from their respective rolls 33, 34 and 35 to the shoulder 25 and the groove 26. A roller 36 (Fig. 2) is rotatably mounted in a suitable manner within the slot 27 and between the horizontal legs of the channel-shaped member 24 to guide the screens 30, 31 and 32 from their respective rolls into the grooves provided in the support 24 and the head 10.

The screens 30, 31 and 32 are drawn from their respective rolls and pass through the slot 27 into the shoulder 25 and the groove 26 and thence into the grooves 23-23 provided in the head 10. The width of the screens 30, 31 and 32 are such that they are slidable in their own plane into the grooves 23-23, and when positioned therein they overlap the rectangular opening 18. The rolls 33, 34 and 35 are rotatable about shafts 37-37 mounted vertically between supports 38-38 (Figs. 1 and 3) spacedly mounted on the support 24 to suit the width of the screens 30, 31 and 32. It will be noted from Fig. 6 that screen 30 is positioned against the end of the strips 20-20 positioned around the flange 13 and adjacent to the end of the stock screw 15, that the screen 31 is positioned behind the screen 30 and that the screen 32 is positioned behind the screen 31 when the screens are drawn across the opening 18 of the head 10. The head 10 is designed so as to be of such length that only a relatively narrow clearance is provided between the end of the screw 15 and the screen 30.

A channel-shaped support 39 is formed integrally with the head 10 on the left side of the flange 13 and is provided with a shoulder 40 in the upper leg thereof and a groove 41 in the lower leg thereof which are aligned with and communicate with the grooves 23-23 provided in the horizontal sides of the opening 18. A rectangular slot 42 is provided in the back of the support 39 to allow the screens extending beyond the opening 18 to pass from the support 39 to a takeup shaft 44 rotatably mounted between brackets 45-45 spacedly mounted on the rear of the channel-shaped member 39 to suit the width of the screens. A roller 46 is rotatably mounted in a suitable manner within the opening 42 and between the horizontal legs of the support 39 to guide the screens from the shoulder 40 and the groove 41 to the takeup shaft 44. A suitable type of torque motor 47 is coupled directly to the lower end of the shaft 44 and arranged to be energized from a suitable source of electric potential in order to rotate the shaft 44 and take up the screens 30, 31 and 32 when desired.

A pair of perforated plates 50-50 are slidably positioned in tandem across the opening 18 by means of flanges 51-51 provided at the top and bottom edges of the plates which engage a portion of the grooves 23-23 provided in the head 10. The plates 50-50 are identical in size and shape, and each plate is of such width that it covers one-half of the opening 18. To assemble the plates 50-50 in position across the opening 18 of the head 10 so that they occupy the positions designated A and B on the drawings, one of the plates 50-50 is positioned in the support 24 so that the bottom flange 51 of the plate engages the groove 26 (Fig. 2) while the upper edge of the plate rests against the shoulder 25.

When the plate is in this position it may be

5 slid laterally along the groove 26 and against the shoulder 25 until the flanges 51-51 of the plate enter the grooves 23-23 of the head 10. When the plate reaches the position B, shown on the drawing, a second plate 50 is positioned in the support 24 in the same manner described for the first plate and slid laterally to the left until it enters the grooves 23-23 and assumes position B. In sliding the second plate 50 into the B position across the opening 18, the first plate is pushed across the opening and subsequently will assume the A position, across the opening. In this way, the plates 50-50 completely cover the opening 18 and completely back up the unsupported area of the screens 30, 31 and 32 positioned across the opening.

The perforated plates 50-50 have been described as being a pair of plates because as such they facilitate easy assembly across the opening 18. It is believed to be apparent that the perforated plates 50-50 may be combined into a single perforated plate and the support 24 lengthened to permit such a single plate to be positioned therein so that it may be moved laterally to the left to its operating position across the opening 18. By using two half size plates 50-50 the length of the support 24 may be materially shortened which may be advisable where it is necessary to keep the size of the strainer head to a minimum.

30 Continuous rotation of the stock screw 15 conveys an extrudable material 52 from a suitable supply hopper (not shown) through the head 10 to the screens and the perforated plates. A considerable pressure is built up in the mass of material 52 directly adjacent to the screens as the extrudable material 52 is forced through the screens. Due to the high pressure required to force the extrudable material 52 through the screens 30, 31 and 32, it is necessary to provide a suitable supporting means for the plates 50-50. The flanges 51-51 provided on the top and bottom sides of the plates 50-50 are not intended to hold the plates against the high pressure developed in the material as the material is forced through the screens but are provided merely as 35 means for guiding the plates as they are slid into position across the opening 18.

The means for holding the plates against the pressure developed in the extrudable material 52 disposed in the bore 11 of the head 10 comprises 40 a central yoke 53 and yokes 54-54 which are suspended vertically across the opening 18. The central yoke 53 is identical in size and shape to the yokes 54-54, except for a pad 55 provided on the inner edge thereof for the purpose of overlapping the central joint between the plates 50-50. The yokes are arranged to be movable longitudinally of the head 10 to simultaneously engage the plates 50-50 and press the overlapping portions of the screens tightly against the 45 end of the strips 20-20 positioned in the grooves 23-23 or simultaneously disengage the plates so that they are freely slidable in the grooves 23-23 in a manner hereinafter to be described.

A plurality of lugs 56-56 (Figs. 1, 2 and 6) 50 are equally spaced along the top side of the rectangular flange 13. The lugs 56-56 are formed integrally with the flange 13 in order to obtain maximum strength between them and the head 10. A splined shaft 57 is rotatably mounted in 55 each of the lugs 56-56 in the following manner: Each of the lugs 56-56 is provided with a bore 58 (Fig. 6) to receive a hardened steel bushing 60, which bushing is equal in length to the width of the particular lug in which the bushing is assembled. A splined sleeve 61 is positioned on

that portion of the shaft 57 embraced by the bushing and is of substantially the same length as the bushing. A needle bearing 62 is positioned in the annular clearance formed between the splined sleeve 61 fitted in the shaft 57 and the bushing 60 fitted in the bore 58. Such an assembly is provided in each of the lugs 56-56, whereby the shaft 57 is freely rotatable in each of the lugs.

A plurality of lugs 63-63 are formed integrally with and equally spaced along the lower surface of the rectangular flange 13 of the head 10. The lugs 63-63 positioned along the lower surface of the flange 13 are of the same thickness as and vertically aligned with the lugs 56-56, whereby the openings between the lugs are vertically aligned with each other. A splined shaft 64 is rotatably mounted in each of the lugs 63-63 in exactly the same manner as that in which the shaft 57 is rotatably mounted on the lugs 56-56.

One end of a toggle link 65 is slidably positioned in each of the openings between the lugs 56-56 and 63-63 and is mounted on the splined shafts 57 and 64 in the following manner: The end of each of the links 65-65 positioned between the lugs is provided with a bore 66 in which is pressed a hardened bushing 67. A splined cam 70 is positioned over each portion of the shafts 57 and 64 which is embraced by the end of a link 65. A needle bearing 71 is positioned in the annular clearance formed between the splined cam 70 and the bushing 67.

Each of the toggle links 65-65 is provided with a forked end 72 arranged to slidably receive the ends of the central yoke 53 and yokes 54-54, and is provided with a bore 73 which is aligned with a bore 74 provided in each end of the yokes so that a pin 75 may be passed therethrough to connect the ends of the yokes to the toggle links. A plate 76 is positioned between the yokes 53 and 54-54 to prevent the material through the screens and the plates from dropping on the forked ends 72-72 of the links 65-65 and the pin 75, whereby the material is prevented from collecting on the forked ends of the links and the pin 75 and prevent free movement of the links with respect to the yokes.

When the shafts 57 and 64 are rotated through one revolution, each of the toggle links mounted on the shafts will be urged alternately to the right, and then to the left, assuming that the shafts 57 and 64 were initially in the position shown in Fig. 6 of the drawings. Each associated pair of toggle links 65-65 moves its respective yoke away from the plates 50-50 or toward the plates 50-50 depending upon the position of the cams 70-70 on the shafts 57 and 64. When the cams 70-70 are in the position shown in Fig. 6, the toggle links have drawn their respective yokes against the plates 50-50 which in turn press the overlapping portions of the screens 30, 31 and 32 tightly against the strips 20-20 positioned in the grooves 23-23 and the vertical legs of the flange 13. The narrow edges of the strips cause the plates to exert a high unit pressure against the screens on the strips and press the screens together so as to close the interstices between the screens and seal the opening 18 against leakage of the material 52. This is the operating position of the yokes and the toggle links and the screw 15 may then be operated to force the extrudable material 52 through the screens and through the perforated plates 50-50.

The yokes 53 and 54-54 serve to hold the

plates 50-50 in position against the high pressure developed in the extrudable material 52 as it is forced through the screens by the stock screw. The width of the plate 22 secured along the lower horizontal portion of the flange 13 is of such width that it engages the bottom of the yokes throughout the total outward movement imparted to the yokes by the splined cams positioned on the shafts 57 and 64. By this arrangement the yokes always are aligned within the edge of the plates 21 and 22 and merely slide in and out of the opening 18.

The shafts 57 and 64 which carry the splined cams 70-70 which actuate the links 65-65, one of which is shown in Fig. 6, are arranged to be rotated so as to cause the yokes connected to the links to engage or disengage the plates in a manner hereinafter to be described. A worm gear 80 is keyed on the left end of each of the shafts 57 and 64. A set collar 81 is positioned on the right end of each of the shafts 57 and 64 to prevent lateral movement of the shafts within the lugs 56-56 and 63-63. A shaft 82 is rotatably mounted in suitable bearings 83-83 (Fig. 4) mounted on the support 39 and has a worm 84 positioned on each end thereof so as to mesh with the worm gears 80-80 keyed on the shafts 57 and 64. In this way the shafts 57 and 64 are driven in unison when the shaft 82 is rotated. A worm gear 85 is keyed on the upper end of the shaft 82 and meshes with a worm 86 driven by a suitable motor 87 suitably mounted on the head 10.

When the motor 87 is connected to a suitable source of potential, it rotates the worm 86 which in turn drives the shaft 82 through the worm gear 85 at a predetermined rate of speed. The shaft 82 in turn drives the shafts 57 and 64 in the same direction and at a predetermined rate of speed through the worm gears 80-80 and worms 84-84. Having the cams 70-70 positioned, as shown in Fig. 6, the shafts 57 and 64 need be rotated only one-half revolution to disengage the ends of the yokes from the perforated plates 50-50, and a second one-half revolution of the shafts will bring the yokes back into engagement with the plates 50-50. Due to this arrangement, the motor 87 need not be a reversible type of motor, as one complete revolution of the shafts 57 and 64 will restore the yokes 53 and 54-54 to their normal operating position against the plates 50-50.

It is desirable to incorporate in the control circuit of the motor 87 suitable electrical switching apparatus for terminating the operation of the motor when the yokes have been completely disengaged from the plates 50-50 and again when the yokes have been restored to their normal operating position against the plates 50-50. Only a relatively simple control circuit including suitable limit switches operated by the shafts 57 and 64 need be employed for accomplishing this cycle of operation of the motor 87, and, therefore, a description of a particular circuit that could be employed is unnecessary here since it forms no part of the invention.

While it has been pointed out hereinabove that the screens 30, 31 and 32 and the plates 50-50 may be assembled in position across the opening 18 of the head 10 manually, it is only possible to perform the assembly manually when there is no material 52 in contact with the screens or the perforated plates. When the stock screw is operating to strain the extrudable material 52 through

the screens 30, 31 and 32, a substantial mass of

the material 52 is embedded in the mesh of the screens and the perforations of the plates 50—50. Continued operation of the stock screw causes the screens to become clogged with foreign matter and agglomerates, whereupon it becomes necessary to change the screens. Under these conditions the screens cannot be disengaged manually from the extrudable material 52 which has become embedded into the screens, and it is necessary to provide means for moving the plates and the screens as a unit across the opening 18 so as to place thereacross fresh areas of the screens 30, 31 and 32 and another pair of plates 50—50.

The apparatus employed for changing the screens and the plates consists of a hydraulic cylinder, indicated generally by the numeral 90 (Figs. 1 and 5) which comprises an annular head 91 formed integrally on the end of the support 24, a cylinder 92 clamped between the head 91 and an annular head 93 by a plurality of bolts 94—94. A piston 95 is positioned within the cylinder 92 and is provided with a piston rod 96 which extends through a central bore provided in the head 91 and has the free end thereof secured to a rectangular ram 97 arranged to slide against the shoulder 25 and in the groove 26 provided in the support 24. The hydraulic cylinder 90 is so arranged that when the piston 95 is positioned at the right end of the cylinder it draws the ram 97 to the right so that there is sufficient clearance between the ram and the end of the plate 50 occupying position B across the opening 18 to permit another perforated plate like the plates 50—50 to be inserted therebetween.

Suitable pipes 100 and 101 are secured to the heads 91 and 93, respectively, for admitting or discharging a hydraulic fluid into or from the hydraulic cylinder 90. The pipes 100 and 101 may be connected in a suitable manner to a conventional four-way control valve 102 arranged to admit the hydraulic fluid to the proper end of the cylinder when it is desired to cause a particular movement of the ram 97. A suitable conveyer indicated generally by the numeral 105 is positioned so as to pass beneath the plates 76—76 so as to catch the material emerging from the strainer head 10 and convey it to the particular apparatus in which the material is to be further used or processed.

The ram could also be actuated as described by means of an elongated screw and its associated driving unit, a rack and gear arrangement or other suitable means.

Operation

Let it be assumed that the straining head 10 is to be set up to strain a particular compound such as the compound 52, and that no compound is in the bore 17 of the head 10. The type of compound to be strained determines the mesh of screens to be used in the straining operation. The selected rolls of the straining screens having the proper mesh, such as the rolls 33, 34 and 35, are mounted on the shafts 37—37 carried by the supports 38—38. The screen carried on the roll 34, that is, the screen 31, is a fine mesh screen, which performs the actual screening operation or which limits the size of the particles of foreign matter or agglomerates in the strained compound. The screen 31 is mounted on the supports 38—38 so that when the screens 30, 31 and 32 are positioned across the opening 18, the screen 31 will be sandwiched between the screens 30 and 32, as shown in Fig. 4. Since the screen 31 is the screen which actually does the straining of the com-

ound, the pressure developed in the material 52 as it is strained is against this screen. Therefore, the screen 32, which is a substantially coarser mesh screen than the screen 31, is positioned between the screen 31 and the plates 50—50 to back up the screen 31 and prevent the material from forcing it into the apertures provided in the strainer plates 50—50 and thereby burst the screen. The screen 30 also has a coarse mesh and is positioned between the screen 31 and the end of the stock screw 15.

Having selected the screens 30, 31 and 32 of the desired mesh and having mounted the rolls thereof on the shafts 37—37, the ends of the three screens are aligned with each other, and are passed through the slot 27 and around the roller 36 so that they engage the shoulder 25 and the groove 26 of the support 24. The screens are pushed along the shoulder and the groove until they enter the grooves 23—23 provided in the rectangular flange 13 of the head 10. The screens are drawn across the opening 18 until the ends thereof ride against the shoulder 40 and in the groove 41 provided in the support 39. The screens then pass around the roller 46 and through the slot 42 provided in the support 39 to the takeup shaft 44 rotatably mounted in the supports 45—45. It should be noted that to assemble the screens across the opening 18 in this manner, it is first necessary to energize the motor 87 and permit it to drive the shafts 57 and 64 so as to position the splined cams 70—70 opposite to that shown in Fig. 6 so that the ends of the yokes 53 and 54—54 will be positioned their maximum distance away from the grooves 23—23.

Having assembled the screens 30, 31 and 32 across the opening 18 in this manner, a perforated plate 50 is positioned in the support 24 so that the flange 51 formed on the bottom end of the plate engages the groove 26, while the flange 51 formed on the top of the plate rides against the shoulder 25 of the support and then slid manually from the support 24 into position B across the opening 18 of the head 10, in which position it covers one-half the opening 18. A second perforated plate 50 is then positioned in the support 24 in the above-described manner and slid manually to the left until it occupies position B across the opening 18, and in so doing it pushes the first plate 50 into position A across the opening 18.

The plates are positioned across the opening 18 of the head 10 so that the right and left ends thereof extend slightly beyond the end yokes 54—54 and the joint between the plates falls directly beneath the pad 55 provided on the central yoke 53. Since there is no material 52 in the head 10, it is a relatively simple matter for the operator of the apparatus to manually assemble the screens and plates in the above-described manner so that they are properly aligned with respect to the opening 18, the central yoke 53 and the yokes 54—54.

After positioning the plates across the opening 18, the motor 87 is then energized to rotate the shafts 57 and 64 one-half turn which places each of the cams 70—70 in the position shown in Fig. 6. When the cam 70 operating within each of the toggle links 65—65 is in this position, the toggle links have drawn their respective yokes 70 inwardly to urge the perforated plates 50—50 toward the screens 30, 31 and 32. This movement of the plates serves to compress the screens 30, 31 and 32 together and against the edges of the strips 20—20 positioned around the flange 13. The narrow edges of the strips 20—20 causes a

high unit pressure to be applied to those portions of the screens adjacent to the edges of the strips, which presses the screens together so as to close the interstices between the screens and effect a substantially tight joint between the edges of the screens and the opening 18.

When the yokes are in this position, the means for driving the stock screw may be energized to rotate the screw to force the compound 52 to be strained from the cylinder 14 into the straining head 10. The stock screw will eventually force the compound 52 to be strained from the cylinder 14 into the head 10 and thence through the screens 30, 31 and 32 and the perforated plates 50-50. The strained material emerging from the perforations in the plates will fall directly upon the plates 76-76 and from there onto the conveyer 105, which serves to convey the strained material to the particular apparatus in which it is to be used or processed.

When the apparatus is operating in this manner, the screen 31, which has been described as the fine mesh straining screen, collects all the unmixed particles and the foreign matter of the compound 52, which are of such size that they will not pass through the fine meshes of the screen 31. As the stock screw 15 continues to operate, the screen 31 gradually clogs up with these oversize particles of the material 52, whereupon the pressure required to strain the compound 52 through the screen 31 increases greatly and likewise the temperature of the material 52 within the head 10 increases.

As the screen 31 clogs up it retards the flow of the compound 52 therethrough and the backing up of the material against the screen compresses the screens tightly together so that the fine mesh screen 31 becomes interlocked with the coarse mesh screens 30 and 32. In addition to this fact, the pressure built up in the material 52 which is required to force it through the screen 31 under these conditions becomes so great that portions of the screen lying over the openings in the plates 50-50 are forced partially into the openings, that is, slight dents in the screens occur at each of the openings in the plates, which dents serve to interlock the screens together and to the plates 50-50.

When the pressure and temperature of the material 52 being strained reach a predetermined point, it is an indication that the screen 31 is so clogged up that further straining therewith is unsafe, and the screens 30, 31 and 32 must be changed in order to bring fresh areas of the screens and backing up plates 50-50 into position across the opening 18. When such conditions occur, rotation of the stock screw 15 is terminated and the motor 87 is energized to rotate the shafts 57 and 64 one-half revolution which simultaneously urges the yoke 53 and the yokes 54-54 away from the plates 50-50. This movement of the yokes provides the maximum clearance between the ends of the yokes and the plates.

Assuming that the piston 95 (Figs. 1 and 2) and the ram 97 are positioned at the right end of their stroke, a third perforated plate 50, like the plates 50-50 occupying A and B positions across the opening 18, is positioned in the support 24 in the manner described hereinabove. The valve 102 is operated to admit the hydraulic fluid into the cylinder 90 so that the piston 95 will drive the ram 97 to the left into engagement with the third perforated plate 50. At the same time that the control valve 102 is operated to cause the piston

to move in this direction, the torque motor 47 connected to the takeup shaft 44 to which the screens 30, 31 and 32 are connected is energized and exerts a substantial pull on the screens. The ram 97 moves to the left and slides all three plates 50-50 and the screens 30, 31 and 32 along their own plane as a unit until the third plate 50 assumes the B position across the opening 18. In so doing, the first plate 50 is now positioned in the support 39 and the portion of the clogged screens withdrawn from the opening 18 therewith are taken up by the shaft 44 driven by the torque motor 47. In this manner fresh areas of the screens are positioned across the opening 18 contiguous with the third plate 50. The torque motor 47 must develop sufficient torque to separate the screens from each plate as it is advanced past the slot 42 with the plate by the cylinder 90. Since the material 52 in the strainer head 10 is embedded in the meshes of the screens, it is necessary for the cylinder 90 to exert sufficient lateral force on the plates and screens to cause the screen 30 to sever the compound 52 in the opening 18 from that embedded within its meshes.

The control valve 102 is then operated to admit the hydraulic fluid to the cylinder 90 to return the ram 97 to the right end of its stroke, and a fourth perforated plate like the plates 50-50 is positioned in the support 24 in the above-described manner. After the plate has been positioned in the support, the control valve 102 is again operated to cause the piston 95 and the ram 97 thereby to be advanced to the left thereby sliding the second, third and fourth plates and the screens as a unit across the opening 18 until the fourth plate occupies the B position across the opening 18. The first and second plates 50-50 are now positioned in the support 39 and the portions of the screens withdrawn from the opening with the last insertion of the fourth plate thereacross is taken up by the torque motor 47.

It will be noted that as the plates 50-50 are pushed into the support 39 with the screens, the motor separates the screens from the plates as it takes them up on the shaft 44. This permits the first and second plates so discharged from the opening 18 to be used in the same manner to eject the third and fourth plates when it becomes necessary to again draw fresh areas of the screens across the opening 18.

Due to the interlocking effect produced by the material embedded in the meshes of the screens and in the perforations of the plates and the physical interlocking of the screens with each other and with the perforations of the plate, the plates and the screens move across the opening 18 as a unit when the ram 97 is actuated by the cylinder 90.

As pointed hereinabove, the screen 31 is a fine mesh screen, which performs the straining operation on the compound 52. That is, the screen 31 limits the size of the particles of foreign matter and agglomerates permissible in the strained compound. The screen 32 is as a coarse mesh screen, which backs up the unsupported area of the screen 31 to prevent material from bursting the screen 31 as it is forced therethrough. The screen 30 is positioned between the end of the stock screw 15 and the fine screen 31 for the purpose of carrying off all of the matter collected in the meshes of the screen 31 when the screens are changed.

When the stock screw is operating as described,

the material 52 passes freely through the coarse mesh screen 30 and impinges against the fine straining screen 31, whereupon the particles in the material that are too large for passage therethrough collect on the surface of the screen 31 as the material is forced therethrough. All the matter collected on the screen 31 lies in between the meshes of the coarse screen 30 (Fig. 5). When the screens are changed in the above-described manner, the movement of the screen 30 with the screens and plates severs the compound embedded within the meshes thereof from the mass of compound positioned adjacent to the surface thereof, and carries the compound embedded therein out of the head 10. Since the oversize particles of the material are mixed in with the material embedded within the meshes of the coarse screen 30, they are carried out of the head when the screens are changed. In this way none of the matter collected on the screen 31 will be dragged across the surface of the compound at the end of the stock screw and therefore will not be left in the strainer head.

It is believed to be apparent from the above description that the screen 30 acts as a scavenger screen by making certain that all the agglomerates and foreign matter of the material 52 which would not pass through the fine mesh screen 31 is removed from the strainer head 10. In this way longer periods of operation of the apparatus may be obtained, because if some of the compound which would not pass through the screen were left in the strainer head when the screens are changed, this material would immediately clog up the fresh area of the screen 31 drawn across the opening 18 and thereby shorten the time the apparatus could be operated before the screens must be changed again.

What is claimed is:

1. In an apparatus for straining materials including an elongated cylinder having a stock screw therein for advancing a material to be strained, the improvement which comprises a plurality of rolls of wire mesh screen rotatably mounted so that the screens may be withdrawn from their respective rolls and positioned across the end of the cylinder to strain over-sized particles from material advanced by the stock screw, means provided on the end of the cylinder for supporting that portion of the screens positioned across the end of the cylinder, a perforated plate slidably positioned in said supporting means of the cylinder to back up the screens as the material is forced therethrough by the stock screw, means for selectively clamping the perforated plate tightly against the supporting means to support the plate and the screens against the pressure of the material being forced through the screens, means provided on the supporting means for sliding the plate and screens laterally across the supporting means of the cylinder to advance fresh portions of the screens from their respective rolls and another backing up plate across the end of the cylinder, and means for coiling up the used screens as they are withdrawn from the end of the cylinder.

2. In an apparatus for straining materials including an elongated cylinder having a stock screw therein for advancing a material to be strained, the improvement which comprises a straining head mounted on the end of the cylinder and having a bore therethrough for receiving the end of the stock screw and the material conveyed thereby, a plurality of rolls of

belt-like screens rotatably mounted so that the screens may be slidably positioned across the open end of the straining head to strain the over-sized particles from the material being conveyed through the straining head by the stock screw, a perforated plate slidably positioned across the open end of the straining head to back up the screens as the material is forced therethrough, means for holding the plate across the opening of the screening head, said holding means adapted to selectively urge the plate and the screens tightly against the end of the straining head to support the plate against the pressure of the material being strained and to release the plates so that the belt-like screens and perforated plate may be slidably withdrawn across the opening of the straining head, fluid pressure power means mounted on the straining head for pushing the plates and the clogged up screens supported thereby as a unit laterally across the end of the straining head so as to draw fresh portions of the belt-like screens and backing plates across said opening, means provided on the straining head for supporting the used backing up plate after the previously used plate and screens have been pushed beyond the opening of the straining head, and a motor driven means for exerting sufficient pull on the screens to separate the screens from the backing up plates and coil them up as the screens and plates are withdrawn from the opening by the fluid pressure means.

3. In an apparatus for straining materials including an elongated cylinder having a stock screw therein for advancing a material to be strained, the improvement which comprises a straining head mounted on the end of the cylinder and having a bore therethrough for receiving the end of the stock screw and the material conveyed thereby, a plurality of rolls of wire mesh screens rotatably mounted so that the screens may be drawn across the open end of the straining head, said screens comprise a coarse mesh screen contiguous with the mass of material conveyed by the screw, a fine mesh screen contiguous with said coarse screen to strain oversized particles and lumps of material conveyed by the stock screw and a coarse mesh screen contiguous with the fine screen, a perforated plate slidably positioned across the open end of the straining head and contiguous with the last-mentioned coarse screen, said perforated plate serving to support the screens as the material is forced through the fine mesh screen, said last-mentioned coarse mesh screen serving to prevent the material being strained from rupturing the fine mesh screen at the apertures provided in the perforated plate, means for selectively clamping the plate and screens tightly against the end of the straining head to support the plate and screens against the pressure developed in the material as it is forced through the fine mesh screen or release the plate and screens so that they may be slidably withdrawn from the opening in the straining head, fluid pressure power means provided on the straining head for sliding the plate and clogged screens supported thereby as a unit from the end of the straining head when it is necessary to position fresh portions of the screens and backing up plate across the opening of the straining head, and motor driven means for coiling up the used screens as they are withdrawn from the end of the straining head, said coiling means serving to separate the used screens from the plates, whereby the perforated plate may be used in

subsequent straining operations to support fresh portions of the screens.

4. In an apparatus for straining materials including an elongated cylinder having a stock screw therein for advancing a material to be strained, the improvement which comprises a straining head secured on the end of the cylinder and having a bore therethrough for receiving the end of the stock screw and the material conveyed thereby to be strained, the open end of said straining head being rectangular in shape and having grooves provided in the horizontal sides of the opening, a plurality of rolls of wire mesh screen rotatably mounted so that the screens may be slidably positioned in the grooves in the straining head, a perforated plate slidably positioned in the grooves for supporting the screens as the material is forced therethrough, said belt-like screens consisting of a coarse mesh screen contiguous with the mass of material to be strained, a fine mesh screen contiguous with the coarse mesh screen, a second coarse mesh screen positioned between the fine screen and the perforated plate, said fine mesh screen serving to strain agglomerated particles from the material conveyed thereto by the stock screw, said second coarse mesh screen serving to prevent the material from forcing the fine mesh screen to the apertures of the perforated plate and thereby bursting the screen, means for supporting the perforated plate against pressure of the material being strained, means for selectively urging the supporting means tightly against the plate to press the screens tightly in the grooves provided in the straining head and for releasing the supporting means so as to permit the screens and plate to be slidably removed from the straining head, power means provided on the straining head for engaging the perforated plate so as to slide the plate and the screens interlocked with each other by the material being strained as a unit from the end of the straining head, said first-mentioned coarse mesh screen serving as a scavenger screen in that it carries therewith all the foreign matter and oversized lumps collected on the surface of the fine mesh screen when the screens are slidably withdrawn from the straining head by said power means, whereby the foreign matter and lumps strained out of material will be completely removed from the straining head.

5. In an apparatus for straining materials including an elongated cylinder having a stock screw therein for advancing a material to be strained, the improvement which comprises a straining head secured on the end of the cylinder and having a bore therethrough for receiving the end of the stock screw and the material conveyed thereby, said straining head having a rectangular opening at the free end thereof which is provided with a groove in the horizontal sides of said opening, a plurality of belt-like screens advanced from suitable supply roll and slidably positioned in the grooves so as to cover the rectangular opening of the straining head, at least one of said belt-like screens serving to strain agglomerated particles and foreign matter from the material, a perforated plate slidably positioned in the grooves with the screens so as to cover the rectangular opening of the straining head, said plate serving to support the screens as the material is forced therethrough by the stock screw, a plurality of yokes positioned transversely across the rectangular opening to support the plate and the screens against the pressure of material being forced through the screens by the stock screw, each of said yokes having a link

movably positioned on each end thereof, a pair of cam shafts rotatably mounted on the rectangular end of the straining head, and means for rotating the cam shafts to actuate the links toward the stock screw or away from the end of the straining head as desired, whereby when the links are actuated toward the stock screw the yokes are drawn tightly against the plate so as to press the screens tightly in the grooves of the straining head and when the links are urged away from the stock screw the yokes disengage the plate so that the plate and screens may be slidably withdrawn together from the rectangular opening of the straining head.

6. In an apparatus for straining materials including an elongated cylinder having a stock screw therein for advancing a material to be strained, the improvement which comprises a straining head secured on the end of the cylinder and having a bore therethrough for receiving the end of the stock screw and the material conveyed thereby, said straining head having a rectangular opening at the free end thereof which is provided with a groove on the horizontal sides of the opening, a plurality of belt-like screens advanced from suitable supply rolls and slidably positioned along their own plane in the grooves so as to cover the rectangular opening of the straining head, at least one of said screens serving to strain agglomerates and foreign matter from the material to be strained, a perforated plate slidably positioned in the grooves with the screens so as to cover the rectangular opening and support the screens as the material is forced therethrough by the stock screw, a plurality of yokes positioned transversely across the rectangular opening to support the plate against the pressure of material being forced through the screens by the stock screw, each of said yokes having a link movably positioned on each end thereof, a pair of cam shafts rotatably mounted on the rectangular end of the straining head, means for simultaneously rotating the cam shafts in the same direction to actuate the links toward or away from the end of the straining head as desired, whereby when the links are actuated toward the straining head the yokes are drawn tightly against the plate so as to press the screens tightly in the grooves of the straining head and when the links are urged away from the stock screw the yokes disengage the plate so that the plate and screens may be slidably withdrawn from the rectangular opening of the straining head, and a hydraulic actuated ram mounted on the end of the straining head for sliding the perforated plate and the screens as a unit across the opening of the straining head to advance fresh portions of the belt-like screens across the opening.

7. In an apparatus for straining materials including an elongated cylinder having a stock screw therein for advancing a material to be strained, the improvement which comprises a straining head secured on the end of the cylinder and having a bore therethrough for receiving the end of the stock screw and the material conveyed thereby, said straining head having a rectangular opening at the free end thereof which is provided with a groove on the horizontal sides of the opening, a plurality of rolls of wire mesh screens which are rotatably mounted so that the screens may be slidably positioned in the grooves so as to cover the rectangular opening of the straining head, said screen serving to strain agglomerates and foreign matter from

the material being forced therethrough by the stock screw, a perforated plate slidably positioned in the grooves contiguous with the screens to support the screens as the material is forced therethrough by the stock screw, a plurality of yokes positioned transversely across the rectangular opening to support the plate against the pressure of material being forced through the screens by the stock screw, each of said yokes having a link movably positioned on each end thereof, a pair of cam shafts rotatably mounted on the rectangular end of the straining head for reciprocating the links, means for simultaneously rotating the cam shafts in the same direction to move the links and the yokes toward or away from the end of the straining head as desired, whereby when the links are actuated toward the straining head the yokes are drawn tightly against the plate so as to press the screens tightly in the grooves of the straining head and when the links are urged away from the stock screw the yokes disengage the plate so that the plate and screens may be slidably withdrawn from the rectangular opening of the straining head, a hydraulic actuated ram mounted on the end of the straining head for sliding the perforated plate and the screens as a unit across the opening of the straining head to advance fresh portions of the belt-like screens across the opening, and means provided on the straining head for supporting the perforated plate after it is slidably displaced from the rectangular opening of the straining head, means for taking up the belt-like screens as they are slidably advanced across the opening of the straining head, said takeup means for the screens being positioned with respect to the straining head so as to separate the screens from the perforated plate, whereby the plate may be used again in straining operations with other portions of the belt-like screens.

8. In an apparatus for straining materials including an elongated cylinder having a stock screw therein for advancing a material to be strained, the improvement which comprises a straining head secured on the end of the cylinder and having a bore therethrough for receiving the end of the stock screw and the material to be strained thereby, said straining head having a rectangular opening in the free end thereof and a groove provided in each horizontal side of said opening, a plurality of belt-

like screens advanced from suitable supply rolls and slidably positioned along their own plane in the grooves so as to overlap the rectangular opening of the straining head, at least one of said screens serving to strain agglomerates and foreign matter from the material, means for properly supporting the screen rolls at one end of the opening in line with said grooves, means positioned at the other end of the opening for taking up the screens, a plurality of perforated plates slidably positioned in said grooves contiguous with said screens so as to support the screens when the material is being forced therethrough by the stock screw, means provided at the screen receiving end of the opening for supporting the perforated plates so they may be slid across the rectangular opening, a hydraulic operated ram slidably mounted on the plate supporting means for sliding the plates and the screens from the rectangular opening as a unit to advance fresh portions of the belt-like screens across the opening of the straining head, a plurality of yokes for supporting the plates against the pressure of the material being forced through the screens, means for actuating the yokes to cause them to press the plates and the screens tightly against the grooves in the straining head while the material is being forced through the screens and for disengaging the yokes from the plates so that the plates and screens may be slidably withdrawn as a unit from the rectangular opening by the hydraulic ram, said screen takeup means arranged to be energized simultaneously with the hydraulic ram to exert a substantial pull on the screens and separate them from the plates when they are advanced from the opening.

JOSEPH E. LODGE.
